Primary Examiner — Karen S Acker(74) *Attorney, Agent, or Firm* — Burr & Forman LLP(57) **CLAIM**

The ornamental design for a nonwoven fabric, as shown and described.

DESCRIPTION

FIG. 1 is a front perspective view of a nonwoven fabric, embodying the new design; and,

FIG. 2 is plan view of the nonwoven fabric of FIG. 1. The broken lines surrounding the drawings depict environmental subject matter that forms no part of the claimed design.

1 Claim, 2 Drawing Sheets(56)
